UNITED STATES PATENT OFFICE.

FREDERICK MARTIN, OF POMONA, CALIFORNIA.

ELECTRIC VULCANIZER.

1,073,263.

Specification of Letters Patent.

Patented Sept. 16, 1913.

Application filed July 25, 1912. Serial No. 711,461.

To all whom it may concern:

Be it known that I, FREDERICK MARTIN, a citizen of the United States, residing at Pomona, in the county of Los Angeles and State of California, have invented a new and useful Electric Vulcanizer; and I do hereby declare the following to be a full, clear, and exact description of the invention, such as will enable others skilled in the art to which it appertains to make and use the same.

This invention relates to a new and useful electric vulcanizer, including a device for regulating the amount of heat necessary to properly vulcanize rubber tires and the like.

One of the objects of the invention is the provision of a simple, efficient, desirable and practical vulcanizer, including a device that will automatically open and close the electric circuit, in order to automatically regulate the necessary amount of heat.

The drawing discloses certain features, but in practical fields these features may require alterations, to which the patentee is entitled, provided the alterations are comprehended within the scope of what is claimed.

The invention comprises further features and combination of parts, as hereinafter set forth, shown in the drawings and claimed.

In the drawings:—Figure 1 is a front view of the improved vulcanizer constructed in accordance with the invention. Fig. 2 is a side elevation of the same. Fig. 3 is a view in rear elevation. Fig. 4 is a plan view. Fig. 5 is a bottom plan view showing the construction of the heater. Fig. 6 is a sectional view on line 6—6 of Fig. 5.

Referring to the drawings 1 designates the base of the vulcanizer, which is constructed with a flange 2, and is provided with a plurality of resistance plates 4, which together with the base are to become electrically heated, in order to convert the water in the pipe 5 into steam. Projecting from one of the flanges of the base is an offset portion or extension 3, from which a bracket arm 6 rises. This bracket arm 6 is secured to the extension 3 by the casting 7, which is riveted or otherwise secured at 8 to the extension. The bracket arm is constructed with an overhanging portion 9, in which a rod 10 is vertically movable. This rod 10 is

threaded in the overhanging portion 9, and is provided with a winged head 11, whereby the rod 10 may be adjusted. To the lower end of the rod a revolving plate 12 is swiveled in any suitable manner as shown at 13, the detailed structure of which, however, is not particularly shown. An inner tube of a rubber tire is adapted to be held between the revolving plate and the base of the vulcanizer, in order to be vulcanized.

The end 14 of the tube 5 is secured in any suitable manner at 15 in the flange of the base 1, and threaded in the end portion 14 is a short pipe 16, to which the elbow 17 is threaded, a pipe 18 is threaded into the elbow 17 and terminates in a member 19 to which a hollow tube 20 connects. This tube 20 is curved as shown in Fig. 1 and terminates in a plate 21 provided with a platinum contact 22. The contact 22 operates with a like contact 23 of the plate 24, which in turn is secured at 25 to the member 19. The base 1 is provided with terminals 26 and 27. A wire or lead connects the terminal 27 and the contact 22, while a wire 29 from any suitable source of current supply (not shown) is connected to the terminal 26. A wire 30 also leads from the current supply and connects to the contact 23.

Water from any suitable source (not shown) may be introduced into the pipe 5, where it is converted into steam, and since the resistance plates are constructed of iron, they become highly heated. From this heat the water in the tube 5 is converted into steam, and since the tube 20 is connected to the tube 5, through the member 19, the pipe 18, the elbow 17 and the pipe 16, the said tube 20 expands under the steam pressure, thereby separating the contacts 22 and 23, and since such contacts are in circuit with the current supply, the circuit is made and broken, thereby properly regulating the amount of heat necessary in the resistance plates for vulcanizing rubber tires and the like. In this manner the heat remains substantially constant and uniform. As the heat slightly decreases, the contacts 22 and 23 come together and again the circuit is closed, thereby heating resistance plates.

From the foregoing it is to be observed that there has been devised a novel and

efficient vulcanizer, and one which has been found desirable and practical, owing to the maintenance of a uniformity of heat.

The invention having been set forth, what is claimed as new and useful is:—

In an electric vulcanizer comprising a base provided with an overhanging member, of an adjustable device including a revolving plate between which and the base an automobile tire is adapted to be clamped for vulcanizing, a series of resistance plates adapted to be heated from any suitable source of current supply and arranged in said base, a pipe designed to contain water to be heated by the resistance plates and fixed in said casing and provided with an elbow at one end, a member adjustably connected to said elbow and provided with an

expansible tube terminating in a plate provided with a point constituting a movable contact, a second plate carried by said member and having a point constituting a stationary contact, said stationary and movable contacts being in circuit with the resistance plates, said resistance plates adapted to heat the base and the pipe, and as the heat varies the tube correspondingly expands or contracts so as to open and close the circuit.

In testimony whereof I have signed my name to this specification in the presence of two subscribing witnesses.

FREDERICK MARTIN.
